KEYING ARRANGEMENT FOR RADIO
TRANSMITTERSErich Stutius, Berlin, Germany, assignor to C.
Lorenz Aktiengesellschaft, Berlin-Tempelhof,
Germany, a companyApplication December 17, 1937, Serial No. 180,387
In Germany March 11, 1937

4 Claims. (CL. 178—66)

The present invention relates to an arrangement for keying high frequency transmitters, and permits such equipments to be continuously keyed in a constant rhythm in accordance with 5 telegraph signals in a very simple manner without employing mechanically actuated means. This new arrangement is particularly advantageously employed for keying radio beacons adapted to indicate position and direction to ships, aircraft 10 and other vehicles.

It is frequently desired in connection with high frequency transmitters to obtain keying, a modulation tone, for example, in a continuously constant rhythm, which may be in order of 1 to 15 10 cycles per second, for instance. The signal interval is fixedly related to the gap interval, that is to say, the signal intervals are either longer or shorter than the gaps.

The previously known keying devices of this 20 type have used rotational interrupters, i. e. cam discs which actuate the keying contacts in a pre-determined rhythm. However, this method involves several disadvantages. First of all, considerable expenditure is required on account of 25 the fact, that motor driven means are necessary. On the other hand, the tendency to failures involved in devices of this kind introduces considerable lack of reliability in operation. The requirement with respect to the necessity of 30 continuous constancy of the keying frequency is a further drawback, as these devices must operate independently of voltage variations, for instance, when electromotors are used.

Finally, it is frequently required in such high 35 frequency transmitters to secure a very quick change over from one keying frequency to another, e. g. by actuating a switch. The sole possibility for realizing this requirement in devices operating with rotational cam discs is the availability of a considerable number of different and 40 arbitrarily interchangeable discs, or a number of simultaneously rotating discs and a corresponding number of key contacts which are optionally switched in circuit by means of a switching device. The first mentioned arrangement involves the disadvantage that a changeover from 45 one keying frequency to another cannot be performed solely by operating a switching device, while the keying equipment is essentially complicated on employing the last mentioned method.

The present invention proposes a new keying arrangement according to which the aforesaid disadvantages are obviated, and which permits a changeover from one keying frequency to another in a most simple manner. This is obtained 55 by effecting the keying by means of a relay interrupter, the frequency and signal-to-gap ratio of which is given by the timing of the relays forming part of the interrupter. A changeover from 60 one keying frequency to other such frequencies

is attained by the provision of further timed relays, which are rendered effective or ineffective by a simple switch. This arrangement permits the keying device to be dimensioned so as to provide a great number of different keying frequencies and signal-to-gap ratios and to be adjusted to the desired keying signals merely by actuating a single switch. This switch, for instance, may simultaneously be used for creating a changeover with respect of the modulation frequency to be keyed. The operation reliability of this new keying arrangement is essentially superior over arrangements of this type known in the past, as the novel device completely omits rotational means, and on account of the fact that 15 the relays may be adjusted to operate independently of temperature influences or voltage variations.

The invention will be more readily understood from the following description in conjunction 20 with the attached drawings, in which:

Fig. 1 diagrammatically illustrates two different keying rhythms; Fig. 2 schematically demonstrates a relay interrupter according to the invention, while Fig. 3 shows a schematically circuit 25 arrangement of a radio beacon system for landing aeroplanes and which employs the keying arrangement according to the invention.

Referring to Fig. 1, there is shown at *a* and *b* two examples of keying rhythms within a one 30 second's interval. The signal and the gap intervals are selected according to a given ration.

The Fig. 2 shows one embodiment of the keying arrangement of the invention. Two relays I and II are provided for one keying frequency and 35 these relays may be supplemented by a third relay III for obtaining a second keying frequency. The latter relay is to be connected in circuit by closing the switch *S*. On closing the starting switch *A*, the relay I is energized over: battery *B*, resistance *W1*, and the contacts *3* and *2*. It closes its contact *1* and establishes a circuit for the relay II over: battery *B*, resistance *W2*, thus causing the slow operating relay to attract and to open its contact *2*, whereby the circuit for the relay I 40 is interrupted. This relay releases after the elapse of a given period in which moment it opens its contact *1* included in the circuit of the relay II. This relay is de-energized and caused to release after a given period with the result that its contact *2* is again closed. The relay I is re-energized and the above described operating cycle 45 again commences. In cases that the switch *S* is closed, the relay III is included in the keying operation, and its timing contributes in an additional sense so as to reduce the keying frequency. The contact *2'* likewise controlled by the relay II and which is provided in the keying circuit serves as keying switch. The release of the individual 50 relays forming part of the interrupter arrange- 55 60

ment is adjusted in any known manner by the provision of series or parallel resistors, e. g. the resistances W_1 and W_2 shown in Fig. 2. The periods of make and break are thereby adjusted so as to obtain a given signal-to-gap ratio.

The present invention is by no means limited to the aforesaid embodiment, on the contrary, it will be possible to provide a number of further relays which are either permanently included or 10 intermittently rendered operative or inoperative in order to vary keying frequency.

The above described new keying arrangement is particularly suitable for the keying of direction finding systems, which are adapted to effect

15 position indications to aircrafts and the like. One example for practically applying this keying arrangement is hereinafter described. It may be assumed that a directional signal transmitter of the type utilized in connection with 20 radio beacons for landing airplanes is employed and that this device is adapted to transmit to the pilot the moment when the landing is to be commenced. The principal circuit arrangement of such a device is demonstrated in Fig. 3. The 25 high frequency transmitter which by aid of the horizontal antenna E produces a wall-shaped and upwardly directed radiation is modulated with a predetermined modulation tone of 700 or 1700 cycles per second, for instance, and keyed 30 in a dash rhythm having a given signal-to-gap ratio. The modulation frequency is produced by a low frequency generator, so arranged that either of the modulation frequencies 700 or 1700 cycles per second may be employed merely by 35 actuating the make and break switch S_1 , which opens or closes the circuit in which the condenser C is included. The keying of the transmitter is effected by virtue of the arrangement proposed according to the invention in such a 40 manner that the low frequency generator is connected to or disconnected from the high frequency transmitter in a rhythm which corresponds to the signals to be keyed.

The portion of Fig. 3 within the dotted lines 45 exactly corresponds to the circuit arrangement of Fig. 2, although shown having its contact in their actual positions relative to their corresponding relay windings. The switch S enables a changeover from one keying frequency to another by adding or omitting the relay III in the relay interrupter arrangement. The switch S is then mechanically coupled with the make and break switch S_1 in order to permit a changeover from one modulation frequency to another 50 at the same time as the keying rhythm is changed. The possibility for a change with respect to the keying frequency and to the frequency of modulation involves the advantage that the same transmitting system may arbitrarily be utilized for different purposes, for example, as a first or second pre-signal emitter in 55 radio beacon arrangements for landing airplanes.

The voltage which is utilized for the energization of the relay interrupter arrangement itself 60 and which is supplied by the battery B of Fig. 2, is suitably derived from the main supply portion of the transmitter and rectified in the rectifying device R which may comprise dry rectifiers, for example.

70 The windings of the relays I , II and III are connected in different circuits and in parallel with one another and parallel to the terminals of a potential source, e. g. in parallel to the rectifier R . The contact 1 of relay I forms part

of the circuit in which the winding of relay II is included. The contact 2 of relay II forms part of the circuit of relay I . The contact 3 of relay III is connected in the circuit of relay I . The circuits of the relays I and II also include resistances W_1 and W_2 , respectively, which serve for timing the attraction and the release of the relays I and II . A second contact $2'$ of relay II is included in the circuit of the low frequency generator F for the purpose of keying the transmitter. It will be assumed that the switch S is closed and that all relays are connected in circuit. The system then operates as follows:

When the switch A is closed the circuit for 15 relay I is likewise closed so that this relay is energized and closes its contact 1 so as to energize relay II . This relay reverts its contact 2 with the result that relay III is energized, while its contact $2'$ is opened so as to interrupt the 20 modulation circuit of the transmitter. The relay I is de-energized in response to the tilted contact 2 . This relay releases with delay and opens its contacts 1 whereupon the relay II likewise releases with delay thus opening its 25 contact 2 and closing its contact $2'$ which latter contact closes the modulation circuit of the transmitter so that a new signal commences. The previously energized relay III opens its contact 3 and this contact is not closed before relay 30 III releases and reverts its contact 2 . Signals as shown in Fig. 1b are then transmitted. When switch S is moved to its open position the relay III is ineffective so that signals of shorter duration corresponding to the representation of Fig. 35 1a are transmitted. At the same time switch S is moved, the tone of the low frequency generator F is changed by connecting the condenser C in circuit by means of the contact S_1 .

What is claimed is:

1. A keying arrangement for producing a series of regularly spaced impulses of predetermined length and frequency comprising a plurality of circuits arranged in parallel with one another and in series to a current source, a plurality of 45 relays each having its winding connected in the appertaining circuit, contacts controlled by each of said relays arranged in a corresponding circuit with a winding of another of said relays to render said relays alternately effective, and 50 means operatively associated with each relay for determining the attraction and the release time of said relay.

2. An arrangement according to claim 1 comprising means for arbitrarily rendering a number of said relays effective or ineffective to select a desired keying frequency, and means for simultaneously selecting a predetermined appertaining modulation frequency.

3. An arrangement according to claim 1, in 60 which said relays are equally or differently timed, comprising means for arbitrarily rendering a number of said relays effective or ineffective to select a desired keying frequency, 65 means for simultaneously selecting a predetermined appertaining modulation frequency, and means connecting said arrangement to a directional radio beacon transmitting system.

4. An arrangement according to claim 1, further comprising means for arbitrarily rendering a selected number of said relays effective or 70 ineffective.

ERICH STUTIUS.
